US00D887688S

(12) **United States Design Patent** (10) Patent No.: **US D887,688 S**
(45) Date of Patent: **** Jun. 23, 2020**

(54) **SHOE**

(71) Applicant: **PUMA SE**, Herzogenaurach (DE)
(72) Inventor: **Carly McKenzie**, Nuremberg (DE)
(73) Assignee: **PUMA SE**, Herzogenaurach (DE)
(**) Term: **15 Years**
(21) Appl. No.: **29/673,313**
(22) Filed: **Dec. 13, 2018**

(57) **CLAIM**

The ornamental design for a shoe, as shown and described.

DESCRIPTION

FIG. 1 is a left and front perspective view of an ornamental design for a shoe;

FIG. 2 is a front elevational view of the shoe of FIG. 1;

FIG. 3 is a rear elevational view of the shoe of FIG. 1;

FIG. 4 is a right side elevational view of the shoe of FIG. 1;

FIG. 5 is a left side elevational view of the shoe of FIG. 1;

FIG. 6 is a top plan view of the shoe of FIG. 1; and,

FIG. 7 is a bottom plan view of the shoe of FIG. 1.

The dash-dash-dash broken lines are included for the purpose of illustrating portions that form no part of the claimed design.

1 Claim, 6 Drawing Sheets
